UNITED STATES PATENT OFFICE

2,460,931

OCARINA

William W. Gretsch, Forest Hills, N. Y., assignor
to The Fred. Gretsch Manufacturing Company,
Brooklyn, N. Y., a corporation of New York

Application December 4, 1944, Serial No. 566,611

5 Claims. (Cl. 84—380)

1

My invention relates to ocarinas and refers particularly to ocarinas composed of only two parts or elements.

One object of my invention is ocarinas composed of only two parts.

Another object of my invention is ocarinas in which all of the parts are capable of being molded from plastics or other suitable material.

Another object of my invention is ocarinas in which the air passage is contained entirely within one element of the device.

Another object of my invention is ocarinas in which there is no possibility of leakage of air during its passage into the device.

Another object of my invention is ocarinas in which the accuracy of the tonal effects is determined during the production of the device and which cannot be changed, or injured, by any displacement of parts through accident to the original construction.

Another object of my invention is ocarinas comprised of as few parts as possible, thus enabling its construction to be simple and economic.

The above mentioned, and other valuable features of my device will be evident upon a consideration of my specification and its accompanying drawings.

In the accompanying drawings illustrating one form of an ocarina of my invention, similar parts are designated by similar numbers.

Figure 1 is an exterior view of a finger element form of an ocarina of my invention.

Figure 2 is an exterior view of a thumb element of the same form of ocarina shown in Figure 1.

Figure 3 is a top plan view of the ocarina of Figures 1 and 2.

Figure 4 is an interior view of the finger element and thumb element of the device of Figure 1, separated from each other in order to show the coordination of the several elements when the device is in closed form.

Figure 5 is a section through the line 5—5 of Figure 3.

The particular form of a device of my invention shown in the accompanying drawings comprises a finger element 10, so called because the apertures therein are opened and closed by the fingers of the player; and a thumb element 11 so called because the apertures therein are opened and closed by the thumbs of the player.

These two elements of my device have the same exterior edge contours, so that when placed in contact with each other they will present the appearance shown in Figures 3 and 5.

The finger element 10 is interiorly concave and

2

is partially extended into the interiorly concave mouthpiece 12. Within the concave portion of the mouthpiece 12 the side of the finger element 10 is extended to form a barrier 13 and the extended end portion of the mouthpiece 12 has a cut-out forming a recess 14. The edge 15 of the finger element 10 is a plane in order that it may contact the corresponding edge plane 15' of the thumb element. The finger piece 10 has a number of holes 16, 16 for the production of various tonal effects in the usual manner of using ocarinas.

The thumb element 11 is interiorly concave and is partially extended into the interiorly concave mouthpiece 12' corresponding in exterior contour to the mouthpiece 12 of the finger element 10. Within the concave portion of the mouthpiece 12', the side of the thumb element 11 is extended to form a barrier 13' and the extended end portion of the mouthpiece 12' has a cut-out forming a passageway 14'. The edge 15' of the thumb element 11 is a plane in order that it may contact the corresponding edge plane 15 of the finger element 10. The thumb piece 11 has a number of holes 16', 16' for the production of various tonal effects in the usual manner in the use of ocarinas. An air passage 17 extends through the end portion of the mouthpiece 12' into the concave space of the thumb element 11, the upper wall 18 of the air passage 17 being extended upwardly toward the outer end of the mouthpiece 12' forming an extended member 19 which is inserted within the recess 14 of the finger piece 10 when the two elements are placed in contact with each other to form the completed ocarina. It will be noticed that the air passage 17 is entirely enclosed within the mouthpiece 12' of the thumb element 11.

In producing the ocarinas of my invention, the edges of the thumb element and of the finger element are abutted upon each other and firmly secured to each other. This can be accomplished by inserting the studs 20, 20, 20 of the finger element into the recesses 21, 21, 21 of the thumb element and thus maintaining frictional contact of the two members, or by cementing or otherwise attaching them to each other.

In operation air is blown through the air passage 17 of the thumb element into the tonal chamber formed by the concave portion of the finger element and of the thumb element, and that different tones may be produced by opening and closing the proper apertures.

It will be noted from the above that the ocarina of my invention can be formed from only two

molded elements of a suitable plastic or other suitable molded material, thus reducing the cost of production and assembling to a minimum.

It will be further noted that, as the air passage of my device is completely within the thumb element, there can be no loss, or leakage, of air during its introduction into the tonal chamber thus insuring the production of an unvarying tone.

It will be further noted that there are no elements, or parts in my ocarinas which can be accidentally misplaced or loosened, thus further insuring constant desired tonal effects.

It will be further noted that as all of the parts of my ocarinas are produced in the molding of its two elements, accuracy of tones can be accomplished during its production.

The above and other valuable features of the ocarinas of my invention will be evident upon a consideration of their construction as set forth herein.

I do not limit myself to the particular size, shape, arrangement or material of parts as specifically shown and described, as these are given solely for the purpose of clearly describing my invention.

What I claim is:

1. In an ocarina, in combination, a pair of complementary interiorly concave elements forming a tonal chamber, a complementary interiorly concave extended mouthpiece portion carried by each of said elements, a duct formed in one of said mouthpiece portions having an entirely enclosed air passage passing therethrough and extending from its exterior end portion into the tonal chamber.

2. In an ocarina, in combination, an interiorly concave finger element with an extended mouthpiece portion, a complementary interiorly concave thumb element having a complementary extended mouthpiece portion, a tonal chamber formed by said finger element and said thumb element, a duct formed in one of said elements having an entirely enclosed air passage passing

35

40

therethrough and extending from its exterior end portion into its portion of said tonal chamber.

3. In an ocarina, in combination, a pair of molded complementary interiorly concave elements forming a tonal chamber, a complementary interiorly concave extended mouthpiece portion formed as an integral part of each of said elements, a duct formed in one of said mouthpiece portions having an entirely enclosed air passage passing through said one mouthpiece portion and extending from its exterior end portion into its portion of the tonal chamber.

4. In an ocarina, in combination a pair of complementary interiorly concave elements forming a tonal chamber, a complementary interiorly concave extended mouthpiece portion formed as an integral part of each of said elements, a duct formed in one of said mouthpiece portions having an entirely enclosed inclined air passage passing through said one mouthpiece portion and extending from its exterior end portion into its portion of the tonal chamber.

5. In an ocarina, in combination, an interiorly concave finger element with an extended mouthpiece portion, a complementary interiorly concave thumb element having a complementary extended mouthpiece portion, a tonal chamber formed by said finger element and said thumb element, a duct formed in the mouthpiece portion of said thumb element having an entirely enclosed inclined air passage passing therethrough and extending from its exterior end portion into its portion of said tonal chamber.

WILLIAM W. GRETSCH.
